(57) **ABSTRACT**

The present disclosure relates to a signal processing device and an image display apparatus including the same. The signal processing device includes a synchronizer configured to perform Fourier transform based on the received baseband signal, and an equalizer configured to extract a pilot signal from a signal from the synchronizer, to calculate a channel transfer function value of the extracted pilot signal, and to selectively perform time interpolation based on the calculated channel transfer function value. Thus, time interpolation is selectively performed based on the channel.

**CROSS-REFERENCE TO THE RELATED
APPLICATION**

Pursuant to 35 U.S.C. § 119, this application claims the benefit of earlier filing date and right of priority to International Application No. PCT/KR2020/005575, filed on Apr. 28, 2020, the contents of which are hereby incorporated by reference herein in its entirety.

**BACKGROUND OF THE PRESENT
DISCLOSURE**

1. Field of the Present Disclosure

The present disclosure relates to a signal processing device and an image display apparatus including the same.

2. Description of the Related Art

A signal processing device is a device for receiving and processing a terrestrial digital broadcasting signal and a mobile communication signal.

The signal processing device receives an RF signal, including noise from a communication channel, via an antenna, and performs signal processing on the received RF signal.

For example, while processing a signal, the signal processing device performs time interpolation and frequency interpolation using a pilot signal in a received baseband signal, and then, performs channel estimation and processes a signal based on the channel estimation.

However, when a current channel is a channel, the wireless channel, the state of which is rapidly changed over time, that is, a mobile channel, if time interpolation is performed, the accuracy of time interpolation is remarkably lowered, and after time interpolation with significantly lowered accuracy is performed, channel estimation accuracy is lowered.

In particular, when a terrestrial broadcasting signal is passed through a mobile channel, if time interpolation is performed, there is a problem in that a defect is present in a broadcasting image.

SUMMARY OF THE PRESENT DISCLOSURE

It is an object of the present disclosure to provide a signal processing device and an image display apparatus including the same for selectively performing time interpolation based on the channel.

It is another object of the present disclosure to provide a signal processing device and an image display apparatus including the same for stably ensuring data even in a mobile channel environment.

In accordance with an aspect of the present disclosure, the above objects can be accomplished by providing a signal processing device and an image display apparatus including the same, including a synchronizer configured to perform a Fourier transform based on the received baseband signal, and an equalizer configured to extract a pilot signal from a signal from the synchronizer, to calculate a channel transfer function value of the extracted pilot signal, and to selectively perform time interpolation based on the calculated channel transfer function value.

In accordance with another aspect of the present disclosure, a signal processing device and an image display apparatus including the same, including a synchronizer configured to remove a guard band based on the received baseband signal, and an equalizer configured to extract a pilot signal from a signal received from the synchronizer, to calculate a channel transfer function value of the extracted pilot signal, and to selectively perform time interpolation based on the calculated channel transfer function value.

BRIEF DESCRIPTION OF THE DRAWINGS

The above and other objects, features and other advantages of the present disclosure will be more clearly understood from the following detailed description taken in conjunction with the accompanying drawings, in which:

FIG. 1 is a diagram illustrating a radio frequency (RF) signal receiving system according to an embodiment of the present disclosure;

FIG. 2A is a diagram showing an example of an image display apparatus according to an embodiment of the present disclosure;

FIG. 2B is a diagram showing another example of an image display apparatus according to an embodiment of the present disclosure;

FIG. 3 is an internal block diagram of the image display apparatus of FIG. 2A;

FIG. 4 is an internal block diagram of the controller of FIG. 3;

FIGS. 5A to 5B are diagrams for explaining a static channel and a mobile channel;

FIGS. 6A to 6C are diagrams for explaining interpolation based on a pilot signal;

FIG. 7 is a flowchart of a method of operating a signal processing device related to the present disclosure;

FIG. 8 is a flowchart of a method of operating a signal processing device according to an embodiment of the present disclosure;

FIG. 9A is a block diagram illustrating an RF signal receiving system according to an embodiment of the present disclosure;

FIG. 9B is a block diagram illustrating an example of an RF receiving device according to an embodiment of the present disclosure;

FIG. 9C is a block diagram illustrating an example of an RF receiving device according to another embodiment of the present disclosure;

FIG. 9D is an internal block diagram showing an example of the signal processing device of FIG. 9B or 9C; and

FIGS. 10 to 12 are diagrams for explaining an operation method of FIG. 8.

**DETAILED DESCRIPTION OF THE
PREFERRED EMBODIMENTS**

Hereinafter, embodiments of the present disclosure will be described in further detail with reference to the accompanying drawings.

In the following description, the terms "module" and "unit", which are used herein to signify components, are merely intended to facilitate explanation of the present disclosure, and the terms do not have any distinguishable difference in meaning or role. Thus, the terms "module" and "unit" may be used interchangeably.

FIG. 1 is a diagram illustrating a radio frequency (RF) signal receiving system according to an embodiment of the present disclosure.

Referring to FIG. 1, an RF signal receiving system 10 according to an embodiment of the present disclosure may include a wireless signal transmitting device 10 for transmitting an RF signal CA, and a wireless reception device 80 for receiving the RF signal CA.

The wireless reception device 80 according to an embodiment of the present disclosure may be an RF receiving device for improving channel estimation accuracy in response to various communication channels or broadcast channel environments.

To this end, an RF receiving device 80 (refer to FIG. 9A) according to an embodiment of the present disclosure may include a signal processing device 520 (refer to FIG. 9B) including a synchronizer 521 (refer to FIG. 9B) for performing Fourier transform based on a received baseband signal and an equalizer 523 (refer to FIG. 9B) for extracting a pilot signal from the signal received from the synchronizer 521 (refer to FIG. 9B), calculating a channel transfer function value of the extracted pilot signal, and selectively performing time interpolation based on the calculated channel transfer function value.

Accordingly, time interpolation may be selectively performed based on the channel. In particular, data may be stably ensured even in a mobile channel environment. In addition, channel estimation accuracy may be improved.

The mobile channel may be a channel, the wireless channel state of which is rapidly changed over time, and may be a time-varying fading channel.

The mobile channel detected by the signal processing device 520 may correspond to a channel that is changed by a Doppler frequency (Doppler speed) over time.

The RF receiving device 80 (refer to FIG. 9A) according to another embodiment of the present disclosure may include the signal processing device 520 (refer to FIG. 9B) including a synchronizer 521 (refer to FIG. 9B), for removing a guard band based on a received baseband signal, and the equalizer 523 (refer to FIG. 9B) for extracting a pilot signal from the signal received from the synchronizer 521 (refer to FIG. 9B), calculating a channel transfer function value of the extracted pilot signal, and selectively performing time interpolation based on the calculated channel transfer function value.

Thus, time interpolation may be selectively performed based on the channel. In particular, data may be stably ensured even in a mobile channel environment. In addition, channel estimation accuracy may be improved.

The RF signal CA of FIG. 1 may be a digital broadcasting signal, and in this case, the RF receiving device 80 of FIG. 1 may be included in an image display device 100 (refer to FIG. 2A) such as a TV or a mobile terminal 100b (refer to FIG. 2B) such as a cellular phone or a tablet terminal.

The RF signal CA may be a broadcasting signal based on the ATSC 3.0 standard.

FIG. 2A is a diagram showing an example of an image display apparatus according to an embodiment of the present disclosure.

Referring to FIG. 2A, the image display apparatus 100 of FIG. 2A may include a display 180 and may also include the RF receiving device 80 described with reference to FIG. 1.

The image display apparatus 100 of FIG. 2A may include a signal processing device that performs Fourier transform based on a received baseband signal, extracts a pilot signal after performing Fourier transform, calculates a channel transfer function value of the extracted pilot signal, and selectively performs time interpolation based on the calculated channel transfer function value.

Accordingly, time interpolation may be selectively performed based on the channel. In particular, data may be stably ensured even in a mobile channel environment. In addition, channel estimation accuracy may be improved.

5 The image display apparatus 100 of FIG. 2A may include a signal processing device that removes a guard band based on a received baseband signal, extracts a pilot signal after removing the guard band, calculates a channel transfer function value of the extracted pilot signal, and selectively 10 performs time interpolation based on the calculated channel transfer function value.

Accordingly, time interpolation may be selectively performed based on the channel. In particular, data may be stably ensured even in a mobile channel environment. In 15 addition, channel estimation accuracy may be improved.

FIG. 2B is a diagram showing another example of an image display apparatus according to an embodiment of the present disclosure.

Referring to FIG. 2B, the mobile terminal 100b of FIG. 2B may include a display 180b and may also include the RF receiving device 80 described in FIG. 1.

The mobile terminal 100b of FIG. 2B may include a signal processing device that performs Fourier transform based on a received baseband signal, extracts a pilot signal 25 after performing Fourier transform, calculates a channel transfer function value of the extracted pilot signal, and selectively performs time interpolation based on the calculated channel transfer function value.

Accordingly, time interpolation may be selectively performed based on the channel. In particular, data may be stably ensured even in a mobile channel environment. In 30 addition, channel estimation accuracy may be improved.

The mobile terminal 100b of FIG. 2B may include a signal processing device that removes a guard band based on 35 a received baseband signal, extracts a pilot signal after removing the guard band, calculates a channel transfer function value of the extracted pilot signal, and selectively performs time interpolation based on the calculated channel transfer function value.

40 Accordingly, time interpolation may be selectively performed based on the channel. In particular, data may be stably ensured even in a mobile channel environment. In addition, channel estimation accuracy may be improved.

FIG. 3 is an internal block diagram of the image display apparatus of FIG. 2A.

Referring to FIG. 3, the image display apparatus 100 according to an embodiment of the present disclosure includes a broadcast receiver 105, an external device interface 130, a memory 140, a user input interface 150, a sensor unit (not shown), a signal processor, the display 180, and an audio output device 185.

The broadcast receiver 105 includes a tuner module 110, a demodulator 120, a network interface 135, and an external device interface 130.

55 Unlike the embodiment of FIG. 3, the demodulator 120 may be included in the tuner module 110.

Further, unlike the embodiment of FIG. 3, the broadcast receiver 105 may include only the tuner module 110, the demodulator 120, and the external interface 135, i.e., without including the network interface 135.

60 The tuner module 110 may tune a Radio Frequency (RF) broadcast signal corresponding to a channel selected by a user or all the previously stored channels, among RF broadcast signals received via an antenna (not shown). In addition, the tuner module 110 may convert the tuned RF broadcast signal into an intermediate frequency signal or a baseband signal (baseband image signal or baseband audio signal).

For example, if the selected RF broadcast signal is a digital broadcast signal, the tuner module 110 converts the digital broadcast signal into a digital IF signal (DIF), and if the selected RF broadcast signal is an analog broadcast signal, the tuner module 110 converts the analog broadcast signal into a baseband image or an audio signal (CVBS/SIF). That is, the tuner module 110 may process the digital broadcast signal or the analog broadcast signal. The analog baseband image or the audio signal (CVBS/SIF), which is output from the tuner module 110, may be directly input to the signal processor.

The tuner module 110 may include a plurality of tuners to receive broadcast signals of a plurality of channels. Alternatively, the tuner module 110 may be a single tuner which receives broadcast signals of a plurality of channels simultaneously.

The demodulator 120 may receive the digital IF (DIF) signal converted by the tuner module 110, and may demodulate the digital IF signal.

For example, the demodulator 120 may convert the digital IF (DIF) signal, which is converted by the tuner module 110, into a baseband signal.

Upon performing demodulation and channel decoding, the demodulator 120 may output a stream signal (TS). Here, the stream signal may be a signal obtained by multiplexing an image signal, an audio signal, or a data signal.

The stream signal, output from the demodulator 120, may be input into the signal processor. Upon performing demultiplexing, A/V signal processing, and the like, the signal processor may output video to the display 180 and audio to the audio output device 185.

The external device interface 130 may be connected to an external device (not shown), e.g., a set-top box 50, to transmit or receive data. To this end, the external device interface 130 may include an A/V input and output device (not shown).

The external device interface 130 may be connected, wirelessly or by wire, to an external device, such as a digital versatile disk (DVD), a Blu-ray, a game console, a camera, a camcorder, a computer (laptop computer), a set-top box, and the like, and may perform an input/output operation with the external device.

The A/V input/output device may receive input of image and audio signals of the external device. A wireless communicator (not shown) may perform short range wireless communication with other electronic devices.

By connection with such wireless communicator (not shown), the external device interface 130 may exchange data with an adjacent mobile terminal 160. Particularly, in a mirroring mode, the external device interface 130 may receive device information, information on executed applications, application images, and the like from the mobile terminal 600.

The network interface 135 serves as an interface for connecting the image display apparatus 100 and a wired or wireless network such as the Internet. For example, the network interface 135 may receive contents or data from the Internet, a content provider, or a network operator over a network.

Further, the network interface 135 may include the wireless communicator (not shown).

The memory 140 may store programs for processing and controlling each signal by the signal processor, or may store processed video, audio, or data signals.

In addition, the memory 140 may also temporarily store video, audio, or data signals input via the external device interface 130. Furthermore, the memory 140 may store

information related to a predetermined broadcast channel using a channel memory function of a channel map and the like.

While FIG. 3 illustrates an example where the memory 140 is separately provided from the signal processor, the present disclosure is not limited thereto, and the memory 140 may be included in the signal processor.

The user input interface 150 transmits a signal, input by a user, to the signal processor, or transmits a signal from the signal processor to the user.

For example, the user input interface 150 may transmit/receive user input signals, such as a power on/off signal, a channel selection signal, a screen setting signal, and the like, to and from a remote controller 200; may transfer a user input signal, which is input from a local key (not shown), such as a power key, a channel key, a volume key, or a setting key, to the signal processor; may transfer a user input signal, which is input from a sensor unit (not shown) for sensing a user's gesture, to the signal processor; or may transmit a signal from the signal processor to the sensor unit (not shown).

The signal processor may demultiplex stream, which is input via the tuner module 110, the demodulator 120, a network interface 135, or the external interface unit 130, or may process the demultiplexed signals, to generate and output signals for outputting video or audio.

The video signal processed by the signal processor may be input to the display 180 to be output as a video corresponding to the video signal. Further, the video signal processed by the signal processor may be input to an external output device via the external device interface 130.

The audio signal processed by the signal processor may be output to the audio output device 185. Further, the audio signal processed by the signal processor may be input to the external output device through the external device interface 130.

Although not illustrated in FIG. 3, the signal processor may include a demultiplexer, a video processor, and the like, which will be described later with reference to FIG. 4.

In addition, the signal processor may control the overall operation of the image display apparatus 100. For example, the signal processor may control the tuner module 110 to tune to an RF broadcast corresponding to a user selected channel or a prestored channel.

Further, the signal processor may control the image display apparatus 100 by a user command input via the user input interface 150 or an internal program.

For example, the signal processor may control the display 180 to display an image. In this case, the image displayed on the display 180 may be a still image or a video, or a 2D or 3D image.

In addition, the signal processor may control the display 180 to display a predetermined object in the displayed image. For example, the object may be at least one of an accessed web screen (newspaper, magazine, etc.), an Electronic Program Guide (EPG), various menus, a widget, an icon, a still image, a video, and text.

The signal processor may recognize a user's location based on an image captured by a capturing unit (not shown). For example, the signal processor may recognize a distance (z-axial coordinates) between the user and the image display apparatus 100. Also, the signal processor may recognize x-axial coordinates and y-axial coordinates in the display 180 corresponding to the user's location.

The display 180 converts a video signal, a data signal, an OSD signal, a control signal which are processed by the signal processor, or a video signal, a data signal, a control

signal, and the like which are received via the external device interface **130**, to generate a driving signal.

Further, the display **180** may be implemented as a touch screen to be used as an input device as well as an output device.

The audio output device **185** may output sound by receiving an audio signal processed by the signal processor.

The capturing unit (not shown) captures a user's image. The capturing unit (not shown) may be implemented with a single camera, but is not limited thereto, and may be implemented with a plurality of cameras. The image information captured by the capturing unit (not shown) may be input to the signal processor.

The signal processor may sense a user's gesture based on the image captured by the capturing unit (not shown), a signal sensed by the sensor unit (not shown), or a combination thereof.

The power supply **190** may supply power throughout the image display apparatus **100**. Particularly, the power supply **190** may supply power to the signal processor which may be implemented in a form of a system on chip (SOC), the display **180** to display an image, and the audio output device **185** to output an audio.

Specifically, the power supply **190** may include a converter which converts an alternating current into a direct current, and a dc/dc converter which converts the level of the direct current.

The remote controller **200** transmits a user input to the user input interface **150**. To this end, the remote controller **200** may use various communication techniques, such as Bluetooth, RF communication, IR communication, Ultra Wideband (UWB), ZigBee, and the like. Further, the remote controller **200** may receive video, audio, or data signals output from the user input interface **150**, to display the signals on the remote controller **200** or output the signal thereon in the form of sound.

The above described image display apparatus **100** may be a fixed or mobile digital broadcast receiver capable of receiving digital broadcast.

The block diagram of the image display apparatus **100** illustrated in FIG. 3 is only by example. Depending upon the specifications of the image display apparatus **100** in actual implementation, the components of the image display apparatus **100** may be combined or omitted or new components may be added. That is, two or more components may be incorporated into one component or one component may be configured as separate components, as needed. In addition, the function of each block is described for the purpose of describing the embodiment of the invention and thus specific operations or devices should not be construed as limiting the scope and spirit of the invention.

FIG. 4 is an internal block diagram of the controller of FIG. 3.

Referring to FIG. 4, the signal processor according to an embodiment of the present disclosure includes a demultiplexer **310**, a video processor **320**, a processor **330**, an OSD processor **340**, a mixer **345**, a frame rate converter **350**, and a formatter **360**. In addition, the processor **170** may further include an audio processor (not shown) and a data processor (not shown).

The demultiplexer **310** demultiplexes an input stream. For example, the demultiplexer **310** may demultiplex an MPEG-2 TS into a video signal, an audio signal, and a data signal. Here, the stream signal input to the demultiplexer **310** may be a stream signal output from the tuner module **110**, the demodulator **120**, or the external device interface **130**.

The video processor **320** may process the demultiplexed video signal. To this end, the video processor **320** may include a video decoder **325** and a scaler **335**.

The video processor **325** decodes the demultiplexed video signal, and the scaler **335** scales resolution of the decoded video signal so that the video signal may be displayed on the display **180**.

The video decoder **325** may include decoders of various standards. Examples of the video decoder **325** may include an MPEG-2 decoder, an H.264 decoder, a 3D video decoder for decoding a color image and a depth image, a decoder for decoding an image having a plurality of viewpoints, and the like.

The processor **330** may control the overall operation of the image display apparatus **100** or the signal processor. For example, the processor **330** controls the tuner module **110** to tune to an RF signal corresponding to a channel selected by the user or a previously stored channel.

The processor **330** may control the image display apparatus **100** by a user command input through the user input interface **150** or an internal program.

Further, the processor **330** may control data transmission of the network interface **135** or the external device interface **130**.

In addition, the processor **330** may control the operation of the demultiplexer **310**, the video processor **320**, the OSD processor **340** of the signal processor, and the like.

The OSD processor **340** generates an OSD signal autonomously or according to user input. For example, the OSD processor **340** may generate signals by which various types of information are displayed as graphics or text on the display **180** according to a user input signal. The generated OSD signal may include various data such as a User Interface (UI), various menus, widgets, icons, etc. Further, the generated OSD signal may include a 2D object or a 3D object.

The OSD processor **340** may generate a pointer which can be displayed on the display according to a pointing signal received from the remote controller **200**. Particularly, such pointer may be generated by a pointing signal processor, and the OSD processor **340** may include such pointing signal processor (not shown). Alternatively, the pointing signal processor (not shown) may be provided separately from the OSD processor **340** without being included therein.

The mixer **345** may mix the OSD signal generated by the OSD processor **340** and the decoded video signal processed by the video processor **320**. The mixed video signal is provided to the frame rate converter **350**.

The frame rate converter (FRC) **350** may convert a frame rate of an input video. The frame rate converter **350** may output the input video as it is without converting the frame rate.

The formatter **360** may change the format of an input image signal into an image signal for displaying on the display **180** and output the changed image signal.

The formatter **360** may convert the format of a video signal. For example, the formatter **360** may convert the format of a 3D image signal into any one of various 3D formats, such as a side by side format, a top down format, a frame sequential format, an interlaced format, a checker box format, and the like.

The audio processor (not shown) in the signal processor may process the demultiplexed audio signal, or an audio signal of a predetermined content. To this end, the audio processor **370** may include various decoders.

Further, the audio processor (not shown) in the signal processor may also adjust the bass, treble, or volume of the audio signal.

A data processor (not shown) in the signal processor may process the demultiplexed data signal. For example, when the demultiplexed data signal is encoded, the data processor may decode the encoded demultiplexed data signal. Here, the encoded data signal may be Electronic Program Guide (EPG) information including broadcast information such as the start time and end time of a broadcast program which is broadcast through each channel.

The block diagram of the signal processor illustrated in FIG. 4 is by example. The components of the block diagrams may be integrated or omitted, or a new component may be added according to the specifications of the signal processor.

Particularly, the frame rate converter 350 and the formatter 360 may not be included in the signal processor but may be provided individually, or may be provided separately as one module.

FIGS. 5A to 5B are diagrams for explaining a static channel and a mobile channel.

First, FIG. 5A illustrates an example in which an RF signal output from a base station TRS is received by a mobile terminal 100b of a pedestrian PES or is received by the mobile terminal 100b inside a vehicle VEC.

The mobile terminal 100b of the pedestrian PES may receive the RF signal through a static channel, and the mobile terminal 100b inside the vehicle VEC may receive the RF signal through a mobile channel.

(a) of FIG. 5B is a diagram illustrating an example of a Doppler frequency signal SGa in a static channel. (b) of FIG. 5B is a diagram illustrating an example of a Doppler frequency signal SGb in a mobile channel.

As shown in FIG. 5B, the frequency of the Doppler frequency signal SGb in the mobile channel is higher than the frequency of the Doppler frequency signal SGa in the static channel.

For example, when the moving speed of the pedestrian PES of FIG. 5A is about 4 Km/h, the RF signal may correspond to the Doppler frequency signal SGa in the static channel as shown in (a) of FIG. 5B, and when the moving speed of the vehicle VEC of FIG. 5A is about 80 Km/h, the RF signal may correspond to the Doppler frequency signal SGb in the mobile channel as shown in (b) of FIG. 5B.

FIG. 6A is a diagram for explaining interpolation in the frequency domain and the time domain when an RF signal is an RF signal based on an orthogonal frequency division multiplexing (OFDM) method.

Referring to FIG. 6A, when a pilot signal is extracted from the RF signal, the pilot signal may be indicated in a pilot pattern in the frequency domain on the horizontal axis and the time domain on the vertical axis.

The signal processing device 520 may perform frequency interpolation in a horizontal direction and time interpolation in the vertical direction based on the pilot signal or the pilot pattern.

The signal processing device 520 may acquire an effective symbol or effective data in the RF signal based on this interpolation or the like.

The mobile channel detected by the signal processing device 520 may correspond to a channel that is changed over time due to the Doppler frequency (Doppler speed).

In this case, the channel is changed more over time as the Doppler frequency increases, and thus a channel change between symbols on the time axis in an OFDM symbol may be increased.

The signal processing device 520 may determine a channel change over time using a channel transfer function value of a pilot symbol positioned at an interval dy of the time axis in an OFDM symbol.

5 FIG. 6B is a diagram showing an example of time interpolation in a static channel.

Referring to FIG. 6B, the signal processing device 520 may restore a signal CVa corresponding to the static channel by performing time interpolation based on the pilot signal or the pilot pattern.

10 FIG. 6C is a diagram showing an example of time interpolation in a mobile channel.

Referring to FIG. 6C, the signal processing device 520 may restore a signal CVb corresponding to the mobile channel by performing time interpolation based on the pilot signal or the pilot pattern.

15 In this case, in the mobile channel, when time interpolation is performed, it may be difficult to restore an accurate signal, and accuracy may be remarkably lowered. Thus, in the mobile channel, time interpolation may not be performed.

20 FIG. 7 is a flowchart of a method of operating a signal processing device related to the present disclosure.

Referring to FIG. 7, the signal processing device 520 may extract a pilot signal based on a baseband signal (S710).

The signal processing device 520 may perform time interpolation based on the pilot signal (S720) and may perform frequency interpolation based on the pilot signal (S730).

25 For example, as shown in FIG. 6A, time interpolation and frequency interpolation may be performed based on the pilot signal.

30 Then, the signal processing device 520 may perform time interpolation and frequency interpolation and may then perform channel estimation (S740).

35 As shown in FIG. 7, in the static channel, even if time interpolation and frequency interpolation are performed prior to channel estimation and channel estimation is then performed, channel estimation accuracy may be maintained.

40 However, in the mobile channel, when time interpolation and frequency interpolation are performed prior to channel estimation, the accuracy of time interpolation may be seriously degraded, and thus, even if channel estimation is performed thereafter, channel estimation accuracy may not be maintained.

45 Thus, the present disclosure proposes a method of selectively performing time interpolation based on the channel environment and then performing channel estimation, which will be described with reference to FIG. 8 and the following drawings.

50 FIG. 8 is a flowchart of a method of operating a signal processing device according to an embodiment of the present disclosure.

55 Referring to FIG. 8, the signal processing device 520 may extract a pilot signal based on a baseband signal (S810).

Then, the signal processing device 520 may calculate a channel transfer function value of the extracted pilot signal or pilot pattern (S813).

60 Here, the channel transfer function value may be a channel transfer function value or a CTF value.

Then, the signal processing device 520 may selectively perform time interpolation based on the channel transfer function value of the pilot signal or the pilot pattern (S820).

65 The signal processing device 520 may perform frequency interpolation based on the channel transfer function value of the pilot signal or the pilot pattern (S830).

11

For example, the signal processing device 520 may turn off time interpolation and may perform frequency interpolation when a difference in a channel transfer function value of a pilot signal between the previous subframe and the current subframe is equal to or greater than a threshold. Accordingly, in the case of a mobile channel, time interpolation may be turned off, and thus data may be stably ensured.

In detail, the signal processing device 520 may turn off time interpolation and may perform frequency interpolation when the difference between a representative value of a channel transfer function value of a pilot signal in the previous subframe and a representative value of a channel transfer function value of a pilot signal in the current subframe is equal to or greater than the threshold. Thus, time interpolation may be selectively performed based on the channel. In particular, data may also be stably ensured in a mobile channel environment.

The threshold may vary based on the moving speed or mode of the signal processing device 520. Thus, time interpolation may be selectively performed based on the channel. In particular, data may be stably ensured in a mobile channel environment.

In another example, the signal processing device 520 may perform time interpolation and frequency interpolation when a difference in a channel transfer function value of a pilot signal between the previous subframe and the current subframe is less than the threshold. Accordingly, in the case of a static channel but not a mobile channel, time interpolation and frequency interpolation may be performed, and data may be stably ensured.

Between operation S813 and operation S820, the signal processing device 520 may perform channel estimation based on the channel transfer function value of the pilot signal or the pilot pattern.

For example, the signal processing device 520 may estimate a channel to be a mobile channel when a difference in a channel transfer function value of a pilot signal between the previous subframe and the current subframe is equal to or greater than the threshold. Thus, in the case of a mobile channel, time interpolation may be turned off, and data may be stably ensured. Channel estimation accuracy may be improved.

In another example, the signal processing device 520 may estimate a channel to be a static channel when a difference in a channel transfer function value of a pilot signal between the previous subframe and the current subframe is less than the threshold. Thus, in the case of a static channel, time interpolation and frequency interpolation may be performed, and data may be stably ensured. Channel estimation accuracy may be improved.

FIG. 9A is a block diagram illustrating an RF signal receiving system according to an embodiment of the present disclosure.

Referring to FIG. 9A, the RF signal receiving system 10 according to an embodiment of the present disclosure may include the wireless signal transmitting device 10 for transmitting an RF signal CA, and the RF receiving device 80 for receiving the RF signal CA.

A noise signal, derived from a channel 70, may be added to the RF signal CA transmitted by the wireless signal transmitting device 10, and the wireless reception device 80 may receive the RF signal CA, to which the noise signal is added.

FIG. 9B is a block diagram illustrating an example of an RF receiving device according to an embodiment of the present disclosure.

12

Referring to FIG. 9B, the RF receiving device 80a according to an embodiment of the present disclosure may include the tuner module 110 for receiving an RF signal including noise of a channel and converting the RF signal into a baseband signal, and the signal processing device 520 for performing signal processing on the baseband signal.

In this case, the tuner module 110 may also function as a demodulator. Alternatively, the RF receiving device 80a may also function as the demodulator of FIG. 2.

The signal processor 520 according to an embodiment of the present disclosure may include the synchronizer 521, the equalizer 523, an error corrector 524, and the like.

The synchronizer 521 may perform synchronization based on an input baseband signal.

The synchronizer 521 may perform synchronization based on a mean squared error (MSE).

For example, the synchronizer 521 may perform synchronization based on a mean squared error (MSE) and may perform synchronization again based on an updated mean squared error (MSE).

The signal processing device 520 may calculate an error e, which is a difference between the input baseband signal and a pilot signal, which is a reference signal, and may output a mean squared error (MSE) based on the calculated error e.

The equalizer 523 may perform equalization based on the signal synchronized by the synchronizer 521.

The equalizer 523 may perform synchronization based on a mean squared error (MSE).

For example, the equalizer 523 may perform synchronization based on a mean squared error (MSE) and may perform synchronization again based on an updated mean squared error (MSE).

The equalizer 523 may perform channel equalization using channel information while performing equalization.

The equalizer 523 may perform interference estimation or channel estimation based on the signal synchronized by the synchronizer 521.

The equalizer 523 may perform interference estimation or channel estimation based on a mean squared error (MSE).

For example, the equalizer 523 may perform interference estimation or channel estimation based on a mean squared error (MSE) and may perform interference estimation or channel estimation based on an updated mean squared error (MSE).

The equalizer 523 may estimate that a communication channel or a broadcast channel includes co-channel interference, adjacent-channel interference, single-frequency interference, burst noise, and phase noise.

The equalizer 523 may also estimate a communication channel or a broadcast channel as any one of a static channel, a mobile channel, and the like.

The static channel may include a Rayleigh channel, a Rician channel, and the like, and the mobile channel may include a vehicular channel, a Doppler channel, and the like.

The error corrector 524 may perform error correction based on the signal (equalization signal) equalized by the equalizer 523. In particular, the error corrector 524 may perform forward error correction.

In this case, the mean squared error (MSE) may be performed based on the signal from the equalizer 523.

The error corrector 524 may perform error correction based on the optimized mean squared error (MSE), thereby accurately performing error correction.

The error corrector 524 may accurately perform error correction even in the presence of interference related to burst noise.

13

The error corrector 524 may accurately perform error correction in consideration of that the communication channel is a static channel.

The error corrector 524 may accurately perform error correction in consideration of that the communication channel is a mobile channel.

FIG. 9C is a block diagram illustrating an example of an RF receiving device according to another embodiment of the present disclosure.

Referring to FIG. 9C, an RF receiving device 80b of FIG. 9C may be similar to the wireless reception device 80 of FIG. 9B, but may be different therefrom in that the demodulator 120 is further included between the tuner module 110 and the signal processing device 520.

The tuner module 110 of FIG. 9C may receive an RF signal including noise from a channel and may convert the RF signal into an intermediate frequency signal, and the demodulator 120 may convert the intermediate frequency signal into a baseband signal.

The signal processing device 520 may perform signal processing on the baseband signal from the demodulator 120, as described with reference to FIG. 9B.

FIG. 9D is an internal block diagram illustrating the signal processing device of FIG. 9B or 9C.

Referring to FIG. 9D, the signal processing device 520 of FIG. 9B or 9C may receive a digital signal from an analog-digital-converter (ADC) 702. Here, the digital signal may be a baseband signal.

The signal processing device 520 of FIG. 9B or 9C may include the synchronizer 521, the equalizer 523, and the error corrector 524.

The synchronizer 521 may include a timing restoration unit 712 for performing timing recovery based on a received baseband signal, a prefix remover 714 for removing a cyclic prefix from the signal received from the timing restoration unit 712, a Fourier transform unit 716 for performing fast Fourier transform (FFT) on the signal received from the prefix remover 714, and a guard band remover 718 for removing a guard band from the signal received from the Fourier transform unit 716.

The equalizer 523 may extract a pilot signal from the signal received from the synchronizer 521, may calculate the value of a channel transfer function for the extracted pilot signal, and may selectively perform time interpolation based on the calculated channel transfer function value.

To this end, the equalizer 523 may include a channel estimator 724 for extracting a pilot signal from the signal received from the synchronizer 521, calculating the channel transfer function value of the extracted pilot signal, and performing channel estimation based on the calculated channel transfer function value, and an interpolation unit 722 for performing interpolation based on the calculated channel transfer function value.

The interpolation unit 722 may perform time interpolation and frequency interpolation based on the calculated channel transfer function value.

According to the present disclosure, the interpolation unit 722 may selectively perform time interpolation based on the calculated channel transfer function value.

The equalizer 523 may extract the pilot signal from the signal received from the synchronizer 521, may calculate a channel transfer function value of the extracted pilot signal, and may selectively perform time interpolation based on the calculated channel transfer function value. Accordingly, time interpolation may be selectively performed based on the channel. In particular, data may be stably ensured even

14

in a mobile channel environment. In addition, channel estimation accuracy may be improved.

The equalizer 523 may turn off time interpolation and may perform frequency interpolation when the difference in a channel transfer function value of a pilot signal between the previous subframe and the current subframe is equal to or greater than a threshold. Accordingly, in the case of a mobile channel, time interpolation may be turned off, and thus data may be stably ensured.

10 The equalizer 523 may perform time interpolation and frequency interpolation when a difference in a channel transfer function value of a pilot signal between the previous subframe and the current subframe is less than the threshold. Accordingly, in the case of a static channel but not a mobile channel, time interpolation and frequency interpolation may be performed, and thus data may be stably ensured.

15 The equalizer 523 may estimate a channel to be a mobile channel when a difference in a channel transfer function value of a pilot signal between the previous subframe and the current subframe is equal to or greater than the threshold. Accordingly, in the case of a mobile channel, time interpolation may be turned off, and thus data may be stably ensured. In addition, channel estimation accuracy may be improved.

20 The equalizer 523 may estimate a channel to be a static channel when a difference in a channel transfer function value of a pilot signal between the previous subframe and the current subframe is less than the threshold. Accordingly, in the case of a static channel, time interpolation and frequency interpolation may be performed, and data may be stably ensured. In addition, channel estimation accuracy may be improved.

25 The equalizer 523 may determine whether time interpolation is performed based on the calculated channel transfer function value, before time interpolation is performed. Thus, channel estimation accuracy may be improved, and as a result, data may be stably ensured.

30 The equalizer 523 may turn off time interpolation and may perform frequency interpolation when a difference between a representative value of a channel transfer function value of a pilot signal in the previous subframe and a representative value of a channel transfer function value of a pilot signal in the current subframe is equal to or greater than the threshold. Thus, time interpolation may be selectively performed based on the channel. In particular, data may also be stably ensured in a mobile channel environment.

35 The threshold may vary based on the moving speed or mode of the signal processing device 520. Thus, time interpolation may be selectively performed based on the channel. In particular, data may also be stably ensured in a mobile channel environment.

40 The equalizer 523 may turn off time interpolation and may perform frequency interpolation from the next subframe when a difference in a channel transfer function value of a pilot signal between the previous subframe and the current subframe is equal to or greater than the threshold. Thus, time interpolation may be selectively performed based on the channel. In particular, data may also be stably ensured in a mobile channel environment.

45 The equalizer 523 may turn off time interpolation and may perform frequency interpolation from the current subframe when a difference in a channel transfer function value of a pilot signal between the previous subframe and the current subframe is equal to or greater than the threshold. Thus, time interpolation may be selectively performed based on the channel. In particular, data may also be stably ensured in a mobile channel environment.

The equalizer 523 may turn off time interpolation and may vary the time at which time interpolation is turned off based on the moving speed or mode of the signal processing device 520 when the difference in a channel transfer function value of a pilot signal between the previous subframe and the current subframe is equal to or greater than the threshold. Because the time at which time interpolation is turned off varies, data may be stably ensured adaptively to the moving speed or the mode.

When a first subframe and a second subframe in one frame have different transport formats, the equalizer 523 may perform control to make a threshold for the first subframe and a threshold for a second subframe different from each other. Data may be stably ensured by making thresholds different from each other according to transport formats. In addition, channel estimation accuracy may be improved.

The equalizer 523 may perform channel equalization using channel information after channel estimation or interpolation is performed. For example, the equalizer 523 may perform channel equalization in the time or frequency domain.

Then, the error corrector 524 may include a deinterleaver 732 for performing deinterleaving based on the signal of the equalizer 523, a demapper 734 for performing demapping, and a channel decoder 736 for performing channel decoding. Thus, the error corrector 524 may perform forward error correction, and may finally output bit sequence data.

The signal processing device 520 may determine whether a channel is a mobile channel using a channel transfer function value of a pilot signal positioned along a pilot pattern before time interpolation is performed.

For example, the signal processing device 520 may calculate a difference in a channel transfer function value at the position of a pilot signal between the current symbol and the previous symbol, and may detect whether a channel is a mobile channel based on the calculated difference.

For example, in the case of a broadcast signal according to the ATSC 3.0 standard, a preamble, first/last sub frame boundary symbols (SBSs), and a data symbol have different pilot types and pilot patterns due to the structure of a frame, and thus the signal processing device 520 may use a scattered pilot of the data symbol.

In detail, the signal processing device 520 may calculate a difference in a channel transfer function value during one subframe section, and may determine whether a mobile channel is detected, based on the threshold.

The signal processing device 520 may turn off time interpolation in the case of a mobile channel.

In this case, the signal processing device 520 may turn off time interpolation in the next symbol based on the time at which the mobile channel is detected.

The signal processing device 520 may check information on whether a mobile channel of a previous frame is detected in a corresponding subframe of a next frame, and may turn on or off time interpolation.

The signal processing device 520 may perform control to selectively perform time interpolation base on a channel transfer function value, which rapidly changes over time. Thus, channel estimation accuracy may be improved.

In particular, the signal processing device 520 may detect whether a channel is a mobile channel using a signal before time interpolation and frequency interpolation are performed. Thus, the accuracy of detection of the mobile channel may be improved.

The signal processing device 520 may control the time at which time interpolation is turned off and may minimize delay in the time at which time interpolation is turned off.

The signal processing device 520 may determine whether a channel is a mobile channel based on a difference in a channel transfer function value at the position of a pilot signal between the current symbol and the previous symbol during one subframe section.

The signal processing device 520 may determine the channel to be a mobile channel and may turn off time interpolation when the difference in the channel transfer function value in one symbol section is equal to or greater than the threshold.

The signal processing device 520 may determine the channel to be a mobile channel and may determine a reference for turning off time interpolation according to the threshold.

For example, the signal processing device 520 may determine whether time interpolation is turned off by comparing the difference in the channel transfer function value in one symbol section with the threshold while increasing the Doppler frequency (Hz).

The signal processing device 520 may set the threshold at which to vary time interpolation to OFF from ON before the Doppler frequency becomes 10 to 20 Hz based on the time at which an error occurs due to the Doppler frequency (Hz).

FIGS. 10 to 12 are diagrams for explaining the operation method of FIG. 8.

First, FIG. 10 is a diagram showing an example of the time at which time interpolation is turned on or off as a mobile channel is detected.

Referring to FIGS. 10 to 12, PSa is a frame signal and PSb is a subframe signal.

The frame signal PSa may be used to differentiate frames FR0 and FR1 from each other, and the subframe signal may be used to differentiate subframes SB0, SB1, and SB2 from each other.

Referring to FIGS. 10 to 12, PSd is an effective data signal, PSe is a pilot signal, PSh is a difference in a channel transfer function value, and Psi corresponds to a signal indicating OFF/ON of time interpolation.

The signal processing device 520 may determine whether time interpolation is turned off by comparing the difference in the channel transfer function value with the threshold.

As shown in the drawings, the signal processing device 520 may determine that the difference PSh in the channel transfer function value is equal to or greater than the threshold, may detect the channel to be a mobile channel MCH, and may perform control to turn off time interpolation when the difference PSh in the channel transfer function value is points Ara, Arb, and Ard, which are in a high level.

That is, the signal processing device 520 may turn off time interpolation during a subframe section after the points Ara, Arb, and Ard.

In examples of the drawings, in a section in which time interpolation is turned off, the level of Psi may be a high level, and in a section in which time interpolation is turned on, the level of Psi may be a low level.

The signal processing device 520 may determine that the difference PSh in the channel transfer function value is less than the threshold, may detect a channel as a static channel STH, and may perform control to turn on time interpolation when the difference PSh in the channel transfer function value is the points Arc and Are, which are in a low level.

That is, the signal processing device 520 may turn on time interpolation during a subframe section after the points Arc and Are.

The equalizer 523 in the signal processing device 520 may turn off time interpolation and may perform frequency interpolation from a next subframe when a difference in a channel transfer function value of a pilot signal between the previous subframe and the current subframe is equal to or greater than the threshold. Thus, time interpolation may be selectively performed based on the channel. In particular, data may also be stably ensured in a mobile channel environment.

The equalizer 523 in the signal processing device 520 may turn off time interpolation and perform frequency interpolation from the current subframe when a difference in a channel transfer function value of a pilot signal between the previous subframe and the current subframe is equal to or greater than the threshold. Thus, time interpolation may be selectively performed based on the channel. In particular, data may also be stably ensured in a mobile channel environment.

The equalizer 523 in the signal processing device 520 may turn off time interpolation and may vary the time at which time interpolation is turned off based on the moving speed or mode of the signal processing device 520 when a difference in a channel transfer function value of a pilot signal between the previous subframe and the current subframe is equal to or greater than the threshold. As the time at which time interpolation is turned off varies, data may be stably ensured adaptively to the moving speed or the mode.

When the first subframe and the second subframe in one frame have different transport formats, the equalizer 523 in the signal processing device 520 may perform control to make the threshold for the first subframe and the threshold for the second subframe different from each other.

By varying the threshold based on transport formats, a reference for the mobile channel may be changed, and as a result, the time at which time interpolation is turned off may be changed. As a result, data may be stably ensured. In addition, channel estimation accuracy may be improved.

For example, in the case of FFT=32 K and QAM=64 in the first subframe, the equalizer 523 in the signal processing device 520 may set the threshold for the first subframe to correspond to a difference in a channel transfer function value at a Doppler frequency of 30 Hz.

In another example, in the case of FFT=8 K and QAM=QPSK in the second subframe, the equalizer 523 in the signal processing device 520 may set the threshold for the second subframe to correspond to a difference in a channel transfer function value at a Doppler frequency of 50 Hz.

In another example, in the case of FFT=16 K and QAM=256 in the third subframe, the equalizer 523 in the signal processing device 520 may set the threshold for the third subframe to correspond to a difference in a channel transfer function value at a Doppler frequency of 10 Hz.

The equalizer 523 in the signal processing device 520 may lower the threshold as the computational load of Fourier transform is increased.

The equalizer 523 in the signal processing device 520 may lower the threshold as the amount of data of a modulation method is increased.

The equalizer 523 in the signal processing device 520 may lower the threshold as the moving speed of the signal processing device 520 is increased.

The equalizer 523 in the signal processing device 520 may set the time at which time interpolation is turned on to be earlier as a computational load of Fourier transform is increased.

The equalizer 523 in the signal processing device 520 may set the time at which time interpolation is turned on to be earlier as the amount of data of a modulation method is increased.

5 The equalizer 523 in the signal processing device 520 may set the time at which time interpolation is turned on to be earlier as the moving speed of the signal processing device 520 is increased.

FIG. 11 is a diagram showing a performance test in a 10 mobile channel and a static channel based on the Doppler frequency.

Referring to FIG. 11, a horizontal axis may correspond to a frequency, and a vertical axis may correspond to a channel transfer function value.

15 In more detail, the vertical axis may correspond to a value obtained by performing average summation on a difference in a channel transfer function value between a current symbol and a previous symbol in one symbol section.

In the drawing, THS indicates a threshold of a static 20 channel, and THM indicates a threshold of a mobile channel.

That is, the threshold of the mobile channel may be higher than the threshold of the static channel.

As shown in FIG. 5A, when the pedestrian PES walks, the 25 Doppler frequency may be less than Fa, and a channel transfer function value in a channel transfer function curve CVa may be maintained at 0 and may then increase to PTa.

As shown in FIG. 5B, when the vehicle VEC travels and accelerates, the channel transfer function value in the channel transfer function curve CVa may increase to Lb from La 30 between frequencies Fa and Fb, as shown in FIG. 11.

In this case, the channel transfer function value in the channel transfer function curve CVa may have a value equal to or greater than the threshold THM of a mobile channel.

Time interpolation may be turned on in a section PDab, 35 that is, between frequencies Fa and Fb, but the channel transfer function value is greater than the threshold THM of the mobile channel prior to the frequency Fb, and thus time interpolation may be turned off from the point PTb corresponding to the frequency Fb.

40 Between the frequencies Fc and Fd, the channel transfer function value in the channel transfer function curve CVa may increase to Ld from Lc.

In the section PDcd, that is, between the frequencies Fc and Fd, when time interpolation is turned on, the accuracy 45 of time interpolation may be seriously degraded due to time interpolation in the mobile channel, and an error may occur, as described above.

Thus, in the section PDcd, that is, between the frequencies Fc and Fd, time interpolation may be turned off.

FIG. 12 is a set of diagrams showing an example of a 50 broadcasting image based on whether time interpolation is ON or OFF in a static channel and a mobile channel.

FIG. 12A shows an example of a broadcasting image 510 displayed on the display 180 of the image display apparatus 100 when time interpolation in a static channel is turned on as shown in (a) of FIG. 5B.

As described above, even if time interpolation in a static channel is performed, broadcast signal data may be stably ensured, and thus the broadcasting image 510 may be clearly 55 displayed.

FIG. 12B shows an example of a broadcasting image 511 displayed on the display 180 of the image display apparatus 100 when time interpolation in a mobile channel is turned on, as shown in (b) of FIG. 5B.

60 As described above, when time interpolation in a mobile channel is performed, the accuracy of time interpolation may be remarkably degraded, and thus the accuracy of broadcast

signal data may be degraded, and accordingly, a defective image 511 may be displayed as shown in the drawing.

FIG. 12C shows an example of a broadcasting image 520 displayed on the display 180 of the image display apparatus 100 when time interpolation of the mobile channel is turned off as shown in (b) of FIG. 5B.

As described above, when time interpolation in the mobile channel is turned off, broadcast signal data may be stably ensured, and thus, the broadcasting image 520 may be clearly displayed.

A signal processing device and an image display apparatus according to an embodiment of the present disclosure may include a synchronizer configured to perform a Fourier transform based on the received baseband signal, and an equalizer configured to extract a pilot signal from a signal from the synchronizer, to calculate a channel transfer function value of the extracted pilot signal, and to selectively perform time interpolation based on the calculated channel transfer function value. Accordingly, time interpolation may be selectively performed based on the channel. In particular, data may be stably ensured even in a mobile channel environment. In addition, channel estimation accuracy may be improved.

The equalizer may turn off the time interpolation and perform frequency interpolation when a difference in a channel transfer function value of the pilot signal between a previous subframe and a current subframe is equal to or greater than a threshold. Thus, in the case of a mobile channel, time interpolation may be turned off, and thus data may be stably ensured.

The equalizer may perform the time interpolation and the frequency interpolation when the difference in the channel transfer function value of the pilot signal between the previous subframe and the current subframe is less than the threshold. Accordingly, in the case of a static channel that is not a mobile channel, time interpolation and frequency interpolation may be performed, and thus data may be stably ensured.

The equalizer may estimate the channel to be a mobile channel when a difference in a channel transfer function value of the pilot signal between a previous subframe and a current subframe is equal to or greater than a threshold. Accordingly, in the case of a mobile channel, time interpolation may be turned off, and thus data may be stably ensured. In addition, channel estimation accuracy may be improved.

The equalizer may estimate the channel to be a static channel when a difference in a channel transfer function value of the pilot signal between a previous subframe and a current subframe is less than a threshold. Accordingly, in the case of a static channel, time interpolation and frequency interpolation may be performed, and thus data may be stably ensured. In addition, channel estimation accuracy may be improved.

The equalizer may determine whether the time interpolation is performed based on the calculated channel transfer function value before the time interpolation is performed. Thus, channel estimation accuracy may be improved, and as a result, data may be stably ensured.

The equalizer may turn off the time interpolation and perform frequency interpolation when a difference between a representative value of a channel transfer function value of the pilot signal in a previous subframe and a representative value of a channel transfer function value of the pilot signal in a current subframe is equal to or greater than a threshold. Thus, time interpolation may be selectively performed based

on the channel. In particular, data may also be stably ensured in a mobile channel environment.

The threshold may vary based on the moving speed or mode of the signal processing device. Thus, time interpolation may be selectively performed based on the channel. In particular, data may also be stably ensured in a mobile channel environment.

The equalizer may turn off the time interpolation and perform frequency interpolation from a next subframe when 10 a difference in a channel transfer function value of the pilot signal between a previous subframe and a current subframe is equal to or greater than a threshold. Thus, time interpolation may be selectively performed based on the channel. In particular, data may also be stably ensured in a mobile channel environment.

The equalizer may turn off the time interpolation and perform frequency interpolation from the current subframe when a difference in a channel transfer function value of the pilot signal between a previous subframe and a current 20 subframe is equal to or greater than a threshold. Thus, time interpolation may be selectively performed based on the channel. In particular, data may also be stably ensured in a mobile channel environment.

The equalizer may turn off the time interpolation and vary 25 a time at which the time interpolation is turned off based on a moving speed or mode of the signal processing device when a difference in a channel transfer function value of the pilot signal between a previous subframe and a current subframe is equal to or greater than a threshold. Because the time at which time interpolation is turned off varies, data 30 may be stably ensured adaptively to the moving speed or the mode.

The equalizer may perform control to make a threshold for a first subframe and a threshold for a second subframe 35 different from each other when the first subframe and the second subframe in one frame have different transport formats. Data may be stably ensured by varying the threshold based on the transport formats. In addition, channel estimation accuracy may be improved.

The signal processing device and the image display apparatus including the same may further include an error corrector configured to perform error correction based on a signal from the equalizer. Thus, data may be stably ensured.

The synchronizer may remove a cyclic prefix based on the 45 received baseband signal prior to the Fourier transform, and may remove a guard band after the Fourier transform. Thus, data may be stably ensured.

The synchronizer may perform timing recovery based on the received baseband signal prior to removal of the cyclic 50 prefix. Thus, data may be stably ensured.

A signal processing device and an image display apparatus according to another embodiment of the present disclosure may include a synchronizer configured to remove a guard band based on the received baseband signal, and an 55 equalizer configured to extract a pilot signal from a signal received from the synchronizer, to calculate a channel transfer function value of the extracted pilot signal, and to selectively perform time interpolation based on the calculated channel transfer function value. Accordingly, time interpolation may be selectively performed based on the channel. In particular, data may be stably ensured even in a mobile channel environment. In addition, channel estimation accuracy may be improved.

The equalizer may turn off the time interpolation and 60 perform frequency interpolation when a difference in a channel transfer function value of the pilot signal between a previous subframe and a current subframe is equal to or

21

greater than a threshold. Accordingly, in the case of a mobile channel, time interpolation may be turned off, and thus data may be stably ensured.

Operations performed by a signal processing device or an image display apparatus according to the present disclosure may be embodied as processor-readable code on a processor-readable recording medium. The processor-readable recording medium may include any data storage device that is capable of storing programs or data which is capable of being thereafter read by a processor. The processor-readable recording medium may also be distributed over network coupled computer systems so that the computer readable code is stored and executed in a distributed fashion.

While the present disclosure has been particularly shown and described with reference to exemplary embodiments thereof, it is to be understood that the same is by way of illustration and example only and is not to be taken in conjunction with the present disclosure. It will be understood by those skilled in the art that various changes in form and details may be made therein without departing from the subject matter and scope of the present disclosure.

What is claimed is:

1. A signal processing device for processing a baseband signal corresponding to a radio frequency (RF) signal received through a channel, the signal processing device comprising:

a synchronizer configured to perform a Fourier transform based on the baseband signal; and
an equalizer configured to extract a pilot signal from a signal from the synchronizer, to calculate a channel transfer function value of the extracted pilot signal, and to selectively perform time interpolation based on the calculated channel transfer function value, wherein the equalizer turns off the time interpolation and varies a time at which the time interpolation is turned off based on a moving speed or a mode of the signal processing device when a difference in the channel transfer function value of the pilot signal between a previous subframe and a current subframe is equal to or greater than a threshold.

2. The signal processing device of claim 1, wherein the equalizer turns off the time interpolation and performs frequency interpolation when the difference in the channel transfer function value of the pilot signal between the previous subframe and the current subframe is equal to or greater than the threshold.

3. The signal processing device of claim 2, wherein the equalizer performs the time interpolation and the frequency interpolation when the difference in the channel transfer function value of the pilot signal between the previous subframe and the current subframe is less than the threshold.

4. The signal processing device of claim 1, wherein the equalizer estimates the channel to be a mobile channel when the difference in the channel transfer function value of the pilot signal between the previous subframe and the current subframe is equal to or greater than a second threshold.

5. The signal processing device of claim 1, wherein the equalizer estimates the channel to be a static channel when the difference in the channel transfer function value of the pilot signal between the previous subframe and the current subframe is less than a second threshold.

6. The signal processing device of claim 1, wherein the equalizer determines whether the time interpolation is performed based on the calculated channel transfer function value before the time interpolation is performed.

7. The signal processing device of claim 1, wherein the equalizer turns off the time interpolation and performs

22

frequency interpolation when a difference between a representative value of the channel transfer function value of the pilot signal in the previous subframe and a representative value of the channel transfer function value of the pilot signal in the current subframe is equal to or greater than the threshold.

8. The signal processing device of claim 2, wherein the threshold varies based on the moving speed of the signal processing device or the mode of the signal processing device.

9. The signal processing device of claim 1, wherein the equalizer turns off the time interpolation and performs frequency interpolation from a next subframe when the difference in the channel transfer function value of the pilot signal between the previous subframe and the current subframe is equal to or greater than the threshold.

10. The signal processing device of claim 1, wherein the equalizer turns off the time interpolation and performs frequency interpolation from the current subframe when the difference in the channel transfer function value of the pilot signal between the previous subframe and the current subframe is equal to or greater than the threshold.

11. The signal processing device of claim 2, wherein the equalizer performs control to make a threshold for a first subframe and a threshold for a second subframe different from each other when the first subframe and the second subframe in one frame have different transport formats.

12. The signal processing device of claim 1, further comprising:

an error corrector configured to perform error correction based on a signal from the equalizer.

13. The signal processing device of claim 1, wherein the synchronizer removes a cyclic prefix based on the baseband signal prior to the Fourier transform, and removes a guard band after the Fourier transform.

14. The signal processing device of claim 13, wherein the synchronizer performs timing recovery based on the baseband signal prior to removal of the cyclic prefix.

15. A signal processing device for processing a baseband signal corresponding to a radio frequency (RF) signal received through a channel, the signal processing device comprising:

a synchronizer configured to remove a guard band based on the baseband signal; and
an equalizer configured to extract a pilot signal from a signal received from the synchronizer, to calculate a channel transfer function value of the extracted pilot signal, and to selectively perform time interpolation based on the calculated channel transfer function value, wherein the equalizer turns off the time interpolation and varies a time at which the time interpolation is turned off based on a moving speed or a mode of the signal processing device when a difference in the channel transfer function value of the pilot signal between a previous subframe and a current subframe is equal to or greater than a threshold.

16. The signal processing device of claim 15, wherein the equalizer turns off the time interpolation and performs frequency interpolation when the difference in the channel transfer function value of the pilot signal between the previous subframe and the current subframe is equal to or greater than the threshold.

17. An image display apparatus comprising:
a signal processing device for processing a baseband signal corresponding to a radio frequency (RF) signal received through a channel; and

a display configured to display an image based on a video signal from the signal processing device, wherein the signal processing device comprises: a synchronizer configured to perform a Fourier transform based on the baseband signal; and 5 an equalizer configured to extract a pilot signal from a signal from the synchronizer, to calculate a channel transfer function value of the extracted pilot signal, and to selectively perform time interpolation based on the calculated channel transfer function value, 10 wherein the equalizer turns off the time interpolation and varies a time at which the time interpolation is turned off based on a moving speed or a mode of the signal processing device when a difference in the channel transfer function value of the pilot signal between a 15 previous subframe and a current subframe is equal to or greater than a threshold.

18. The image display apparatus of claim 17, further comprising: a tuner configured to receive the RF signal and to convert 20 the RF signal into the baseband signal.

19. The image display apparatus of claim 17, further comprising: a tuner configured to receive the RF signal and to convert 25 the RF signal into an intermediate frequency signal; and a demodulator configured to convert the intermediate frequency signal into the baseband signal.
